ROAD MACHINE

Carl A. Gustafson, Minneapolis, Minn., assignor
to Caterpillar Tractor Co., San Leandro, Calif.,
a corporation of California

Application June 15, 1932, Serial No. 617,289

53 Claims. (Cl. 37—156)

The present invention relates to road machines, and more particularly to a tool and mounting means therefor. The invention disclosed herein is primarily useful in connection with road maintainers having rubber tired wheels, particularly 5 pneumatic tires.

Road maintaining machines of the type disclosed herein are adapted for use in finishing or refinishing the surfaces of roads, the earth-engaging tool thereof being adapted to plane off the high spots and to work the planed material 10 back and forth across the road to fill the depressions therein and leave a regular, even road surface.

15 The earth-engaging tool may consist of either a plurality of parallel planing blades, and a leveling or distributing blade, or a single cutting blade. With either type of blade, it is highly desirable that the cutting edge of the earth-engaging tool be maintained constantly in the same 20 plane of movement so that a regular and even road surface is obtained. Such tools heretofore have been rigidly connected to the frame of the machine by lift links or screws whereby the depth 25 of cut of the blade may be adjusted and the entire weight of the machine is used to maintain the blade in its cutting position.

During operation, rubber tired wheels, particularly those provided with pneumatic tires, have a tendency to flex or bounce over rough sections 30 of road. Any flexing movement of the tires causes the tool to be forced below the selected cutting plane thereof, while any bouncing action of the tires causes the tool to be lifted above such 35 plane, so it is seen that with a rigid connection from the tool to the frame of the machine, rough sections of road will cause irregular contact of the tool with the surface of the road whereby a wavy or irregular surface is left. This undesirable feature has interfered materially with the 40 successful use of automotive road machines and has limited particularly the speed of such machines, as the flexing and bouncing action increases with higher speeds.

45 This difficulty is overcome in the structure disclosed herein by the provision of a novel mounting means for the earth-engaging tool which provides a flexible, resilient connection between said tool and the frame of the machine while permitting adjustment of the tool to a desired depth or to a desired inclination. This novel mounting means absorbs any movement of the frame due 50 to the flexing or bouncing action of the tires and prevents transmission of such movement to the tool. Furthermore, the earth-engaging tool is

permitted to have a substantially free, floating contact with the surface of the road, adjusting means being provided so that as much weight as desired may be used to press the tool into engagement with the surface of the road. Thus, whether the road be dry and hard, or soft, the earth-engaging tool is adjustable to plane an even road surface at a selected depth. In addition, higher speeds of operation of the road machine are practicable whereby the time required to 5 work a given stretch of road is reduced materially.

Another advantageous feature of the flexible, resilient tool support is that it provides a more effective escape for the tool if it encounters a solid 10 obstruction during operation. As only the tool 15 and circle assembly need be lifted, and not the entire machine, the danger of breakage during operation is practically eliminated.

Statement of invention

It is an object of the invention to provide means in an automotive road machine for absorbing 20 undesired movement of the frame to prevent such movement being transmitted to the tool.

Another object of the invention is to provide 25 mounting means for an earth-engaging tool which permits a substantially free floating engagement therof with the surface of the road.

Another object of the invention is to provide 30 mounting means for an earth-engaging tool whereby said tool has a controlled floating engagement with the surface of the road.

Another object of the invention is to provide 35 adjustable means for varying the portion of the weight of an earth-engaging tool which is carried by the frame of the machine.

Another object of the invention is to provide 40 means for varying the weight which presses an earth-engaging tool into contact with the surface of the road.

Another object of the invention is to provide 45 mounting means for an earth-engaging tool which is readily adaptable to provide a flexible or a rigid mount therefor.

Another object of the invention is the provision 50 of resilient mounting means for an earth-engaging tool.

Another object of the invention is the provision of flexible mounting means for an earth-engaging tool.

Another object of the invention is to provide 55 mounting means for an earth-engaging tool which insures smooth, chatterless operation at relatively high rates of speed in road maintaining work.

Another object of the invention is to provide in

a road machine having a resilient tool support, means for disabling the resilient support whereby a rigid connection is obtained from the tool to the frame.

5 Another object of the invention is the provision of improved adjusting means for an earth-engaging tool.

Other objects will appear as the description progresses.

25 Fig. 8 is a side elevation of the tool and circle assembly.

DESCRIPTION OF MACHINE

25 *Frame and supports therefor*

The frame of the machine is substantially symmetrical with respect to the longitudinal axis thereof and includes two side channels 10, 11 (Figs. 30 1 and 2) which extend substantially the length of

35 the machine and have a slight convergence toward the front end (Fig. 2). These side channels are connected by cross members and braces. In the front end of the machine bolster 12 is riveted to the forward ends of side channels 10 and 11. Said bolster 12 is provided with centrally located journal 13 on the under side thereof which is adapted to receive a draft connection for the tool as described hereinafter. Bolted to the under 40 side of bolster 12 is casting 14 which has a pivotal connection (not shown) with front axle 15, and is provided with centrally located journal 16 on the upper side thereof opposite journal 13 in bolster 12 and adapted to receive said draft connection 45 for the tool.

Front wheels 17 (Fig. 2) are journaled on spindles integral with knuckles 18 which are pivotally mounted in the forked ends of front axle 15 and have steering arms 19 connected by adjustable rod 50 21. Said wheels 17 are provided with suitable pneumatic tires. Right steering arm 19 has lateral extension 22 (Fig. 2) connected by drag link 55 23 (Fig. 1) to arm 24 which is operated by suitable steering mechanism enclosed in housing 26 (Fig. 2). Said steering mechanism is operated by shaft 27 (Figs. 1 and 2) which extends rearwardly to the operator's station and is provided with a hand-wheel 28 (Fig. 1).

Near the front end hanger 29 (Figs. 1 and 2) is 60 provided, the ends thereof being riveted to side channels 10 and 11, respectively, suitable gussets serving to strengthen the connections. Brace rods 31 (Fig. 2) are secured at their forward ends to front axle 15 and converge rearwardly, having a joint pivotal mounting in bracket 32 (Fig. 1) which is secured to the under side of hanger 29.

At the rear end of the machine, side channels 10, 11 are secured to curved channel 33 by suitable brackets, said channel forming a rear bumper.

70 Rear wheels 34, only one of which is shown, are mounted on a rear axle assembly which supports side channels 10 and 11. Rear wheels 34, like front wheels 17, are provided with pneumatic tires. Said rear axle assembly is driven from mo-

5 tor 36, which is suitably supported in the frame, through clutching and transmission mechanism enclosed in housing 37 (Fig. 1). The drive therefore is controlled by gear shift lever 38 and a clutch pedal, not shown, located at the operator's station. Brake pedal 39 controls suitable braking means, not shown.

10 By means of the above-described mechanism the operator is able to control the movements of the road machine.

Shaft 41 is constantly driven from motor 36 and transmits the drive therefrom to reversible clutch means encased in gear box 42 and controlled by levers 43, only one of which is seen in Fig. 1. Levers 43 control power operated adjusting means 15 for the tool as more fully described hereinafter.

20 *Tool support and mounting means therefor (100 series numerals)*

The tool and circle assembly, more specifically described hereinafter, is supported from side channels 10, 11, by screw lift arms or links 100, 101, respectively (Figs. 1 and 6). Said links or arms 100, 101, are identical in construction and mounting, and only one of such members need be 25 described.

Lift link 101 (Fig. 1) is raised and lowered by suitable gearing mounted in housing 102, and driven by extensible telescoping shafts 103, universally connected thereto and to reversible clutch 30 means in gear box 42. Said housing 102 is pivotally mounted in fork 104, the hub of which is journaled in apertured boss 106 of bracket 107, secured to side channel 11. Thus it is seen that lift link 101 is supported universally on the frame 35 of the machine. Lift link 100 is similarly supported.

Lift link 101 is provided with a flexible, resilient connection to the tool and circle assembly. At 40 its lower end, lift link 101, together with cap 111 (Figs. 3 and 6 to 8) secured thereto by bolts 112, form a bearing socket which receives ball 113 secured to cross bar 114 near the outer end thereof. Cross bar 114 is pivotally secured at its inner end to the upright flange of rear cross angle 116 by 45 bolt 117. Cross angle 116 forms a part of the circle supporting frame to be described hereinafter. The outer end of the cross bar 114 is bent forwardly and is provided with apertured boss 123 (Figs. 3 and 6 to 8) which receives bolt 124. Said bolt 124 extends downwardly through an aperture in the horizontal flange of angle 116 and is provided with nut 126 and washer 127 (Figs. 6 and 8). Compression spring 128 surrounds said bolt 124 and is held between washer 50 127 and the horizontal flange of cross angle 116. From the foregoing description it is seen that bar 114 is universally connected intermediate its ends to lift link 101, is pivotally connected at one end to the circle supporting frame, and has a resilient or elastic connection therewith at its other end. Thus cross bar 114 and the end of cross angle 116 adjacent thereto each have corresponding connecting stations whereby a resilient, flexible tool mounting means is provided, said bar 55 114 and said angle comprising a pair of members having offset or spaced pivotal and resilient connections.

Bar 114, it will be observed from Fig. 6, acts as a lever which, because of its intermediate pivotal 60 connection with lift link 101, provides for indirect supporting of the earth-engaging tool structure on the resilient means or spring 128. As a result, the resilient means, which resiliently opposes the weight of the tool structure and floatingly sup- 65 70 75 75

ports the structure with the tool in yielding engagement with the ground, has imposed thereon only a portion of the tool structure weight which would otherwise be normally imposed thereon if the tool structure were to be directly supported on or suspended from the resilient means. Thus, for any given weight of the tool structure, a lighter and smaller size spring may be employed, than would otherwise be permitted by direct supporting of the tool structure on the spring; and at the same time wear on the parts is reduced to a minimum.

Means are provided for limiting the oscillation of cross bar 114 with respect to the circle supporting frame. U-shaped bracket 129 (Figs. 1, 6 and 8) extends over cross bar 114 near its outer end and has its ends bolted to the vertical and horizontal flanges of cross angle 116, respectively. Thus the oscillatory movement of the outer end of cross bar 114 is limited in extent by bracket 129 and cross angle 116.

Means are provided for disabling the flexible, resilient connection between lift link 101 and the tool and circle assembly. Aperture 131 in cross bar 114, and aperture 132 in cross angle 116, are aligned when said cross bar 114 is moved to a horizontal position whereby a bolt inserted through said apertures will provide a rigid connection from lift link 101 to cross angle 116. Thus additional connecting stations are provided on cross bar 114 and the adjacent end of cross angle 116 whereby a rigid tool support may be provided.

Lift link 100 (Figs. 3 and 6) is similarly connected to the left end of cross angle 116, having a ball and socket connection 136 with cross bar 137. Cross bar 137 is pivotally connected at its inner end to said cross angle 116 by bolt 138, and is provided at its outer end with aperture 139. Bolt 141 passing through said aperture and through cross angle 116 is provided with nut 142 and washer 143. Compression spring 144 surrounds bolt 141 and is held between washer 143 and cross angle 116. U-shaped bracket 146 similar to bracket 129 serves to limit oscillation of cross bar 137. Aperture 147 in bar 137, and aperture 148 in angle 116, provide means for disabling the resilient, flexible connection between lift link 100 and the tool and circle assembly.

Thus it is seen that lift links 100, 101 are resiliently and flexibly connected to the tool supporting frame whereby movement of the frame of the machine within the limits of oscillation of cross bars 114, 137 is not transmitted to the tool. Moreover by adjusting said lift links any part or all of the weight of the tool and circle assembly can be supported from the frame of the machine so that the tool is adjustable to have substantially free-floating contact with any type of road surface. In addition the weight which presses the tool into engagement with the road surface may be varied.

Cross angle 116 forms a part of the circle supporting frame comprising said cross angle, drawbars 161, 162 and yoke 163 (Fig. 3). Brackets 164, 166 are bolted to cross angle 116 and the respective rear ends of drawbars 161, 162, while yoke 163 is bolted to said drawbars intermediate their ends. Circle 186, more fully described hereinafter, is revolvably mounted on ledges formed in brackets 164, 166, and at the forward corners of yoke 163. Bolts 167 (Fig. 3) provide adjusting means for preventing play between said circle and the supports therefor.

Said circle supporting frame is provided with a universal draft connection to the frame of the

machine. Drawbars 161, 162, converge forwardly and are joined at their forward ends by connection 168 (Figs. 1 and 2) bolted thereto. Bolt 169 is journaled in connection 168 and is provided with apertured head 170 which receives pin 171, having its ends journaled in universal connection 172. Universal connection 172 is pivoted in journals 13 and 16 in bolster 12 and casting 13, respectively. Thus drawbars 161, 162 can pivot in a vertical plane about the axis of pin 171, can 10 pivot in a horizontal plane about the axis of journals 13, 16, and can rotate about the axis of bolt 169. It is seen, therefore, that the tool and circle assembly is capable of a limited universal movement about a point at the intersection 15 of the axes of pin 171 and universal connection 172 as a center.

To summarize the movements of which the circle is capable, they are, an arcuate movement in a horizontal plane about the vertical axis of 20 journals 13, 16; an arcuate movement in vertical planes containing said axis; oscillation about the axis of bolt 169; and oscillation of the circle about its center. The desired tool adjustment is usually obtained by combinations of these movements. 25

Arcuate movement of the circle in the horizontal plane is obtained by shifting the center of the circle. This adjustment is made through link 173 (Figs. 1, 3 and 6 to 8), the lower apertured end of which is pinned on stud 174 (Figs. 3 and 7) which is welded to cross bar 114. A similar stud 175 is provided on cross bar 137. The upper bent end of link 173 (Fig. 1) is received in apertured lug 176 depending from rack 177 which is slidably mounted on T-bar 178 secured to the frame. Rack 177 is engaged by pinion 179 fast on shaft 180. Said shaft 180 is driven by gearing mounted in housing 181 which is driven by extensible telescoping shafts 182, universally connected thereto, and to reversible clutch mechanism in gear box 42. Link 173 by being connected to bar 114 is unable to transmit slight frame movements to the circle because of the resilient connection between bar 114 and angle 116, previously described. 40

Circle 186 is also adjustable about its center, and for this purpose, rack 183 (Figs. 3 and 7) is provided on the horizontal flange thereof. A pinion, not shown, engages said rack 183 and is driven by gearing in housing 184 (Fig. 1) mounted 50 on yoke 163. Said gearing is driven by reversible clutch means in gear box 42 through extensible telescoping shafts 185 universally connected thereto.

The remaining movements of the circle, 55 namely, arcuate movement in vertical planes containing the axis of journals 13, 16, and oscillation about the axis of bolt 169, are obtained by adjustments of lift links 100, 101.

The tool, comprising the blade, circle and circle 60 supporting framework, considered as a unit, is connected to the main frame of the machine as follows: a front support and draft connection at universal 172, and three adjustable supports, namely, lift links 100, 101, and center shift link 65 173. These three adjustable supports all have resilient connections with the tool unit, so that undesirable movements of the frame are not transmitted to the tool.

Means are provided for supporting a tool from the circle, and while a preferred form of tool is disclosed herein, namely, a multiple blade scraper, other tools such as a single grading blade, or a scarifier, can be equally well secured to the circle 70

which is flexibly and resiliently supported from the frame.

Circle 186 may be formed by casting or from a single piece of angle bent into a circle. Beam 187 (Fig. 1) is provided with central portion 188 bent into a semi-circle of substantially the same radius as the circle; said central portion 188 encompasses approximately one-half of circle 186 and is riveted thereto. End portions 189, 190 (Fig. 6) 10 of the beam extend tangentially from the circle and downwardly, having lower apertured ends for connection to the tool.

In order to rigidly connect the end portions of the beam to the circle, upright angles 191, 192 15 (Figs. 6 and 7) are riveted to respective end portions 189, 190, and to cross angle 193. Brackets 194, 195, are riveted to said angle 193 and to circle 186. In addition, the lower ends of angles 191, 192, are rigidly secured by gussets 196, 197, to 20 the respective lower ends of inclined braces 198, 199, the upper ends of which are riveted to cross angle 193.

Tool construction (200 series numerals)

25 Tool 200 comprises a multiple blade assembly and a leveling or distributing blade. The multiple blade consists of cross angles 201, 202, (Figs. 1, 3 and 8,) to the upright flanges of which smaller cross angles 203, 204, are riveted. A 30 plurality of parallel, equally spaced angles 206 (Figs. 3 and 6) are riveted to the horizontal flanges of angles 201, 202, being perpendicular thereto. A blade 207 is bolted to each of said angles 206.

35 Tool 200 is pivotally connected at the rear edge thereof to end portions 189, 190 of beam 187, and is provided with an adjustable connection to the front of the circle whereby the angle between the circle and the multiple blade may be varied.

40 Brackets 211, 212 (Fig. 6) are riveted to the vertical flange of cross angle 201 and have apertured ears 213, 214, respectively. Said brackets are adjacent respective end portions 189, 190, of beam 187 and bolts 216, 217 provide a pivotal connection theretwixt. Said bolts 216, 217 are journaled in the apertures in ears 213, 214, and in said end portions 189, 190 by tapered washers 218, 219, respectively.

Forwardly converging angles 221, 222 are bolted 50 to angles 203, 204, and have shorter bracing angles 223, 224 (Figs. 3 and 6) riveted thereto. The forward ends of angles 221, 222, extend past angle 204 and are bolted to bracket 226 (Figs. 1, 5, 6 and 8). The central portion of bracket 226 55 forms with cap 227 (Fig. 8) bolted thereto, a socket which receives ball 228 formed on the lower end of screw 229 having nut portion 230. Said screw 229 has threaded engagement with cylindrical housing 231 which is pivoted on pin 232 (Fig. 5) journaled in bracket 233 bolted to beam 188 and circle 186. Bolt 234 provides means for 60 tightening housing 231 on screw 229 to maintain the adjustment thereof. Said nut portion 230 provides a means for adjusting screw 229 to vary the angle between the multiple blades and the circle whereby said multiple blade may be adjusted to a plane parallel to the surface of the road in any vertically adjusted position of the blade and circle.

65 70 The leveling or spreader blade is adjustably supported from the multiple blade. Pairs of angles 236, 237—238, 239, (Fig. 3) are bolted to cross angles 203, 204, near the respective ends thereof, and are spaced apart to receive arms 241, 242 which are pivoted on pins 243, 244, respec-

tively, near the front of said pairs of angles. Said arms 241, 242, bend downwardly at their rear ends (Fig. 8) and respective pairs of brackets, 246, 247, (Figs. 3 and 8) are riveted thereto and to cross angle 248 to which leveling blade 249 is 5 bolted.

Adjustable connecting means are provided whereby blade 249 can be moved in an arc about the axis of pins 243, 244, so that the height of the leveling blade with respect to the surface 10 planed by the multiple blade may be adjusted. There is a connecting means associated with each of arms 241, 242, and as said connecting means are identical in construction, only one will be described in detail.

Brackets 247 bolted to angle 248 (Fig. 8) near the right end thereof are provided with apertured extensions 251 which receive pin 252 (Figs. 6 and 8) on which bolt 253 is pivoted. Bolt 253 (Fig. 4) extends within cylindrical housing 254, said housing having a central portion 256 of smaller diameter with which said bolt has threaded engagement. Collars 257, 258, are welded on housing 254 to position housing 254 for rotation on its support 259. Support 259 is provided with opposite integral trunnions 261 (Figs. 3 and 8) journaled in arms 262, 263 welded to angles 238, 239, respectively. Bolt 264 holds said arms 262, 263 in engagement with said trunnions 261.

Adjusting handle 266 (Figs. 4 and 8) is pivotally 30 mounted on bolt 267, journaled in ears 268 integral with collar 257. Handle 266 when moved to horizontal position is used to rotate housing 254 to raise or lower screw 253. When said handle is moved to its vertical position, it lies between fingers 269 integral with collar 259 whereby housing 254 is locked against rotation, and the adjusted 35 height of leveling blade 249 is maintained.

A similar adjustable connecting means, indicated generally at 271 in Fig. 3, for the leveling 40 blade is provided near the left end thereof; said adjustable connecting means 271 is identical in construction with the one heretofore described.

While my invention has been shown and described in its preferred embodiment, it is to be 45 understood that my invention may be embodied in other forms, and that the scope thereof is to be limited only by the appended claims.

I, therefore, claim as my invention:

1. In a road machine, a frame, a steerable front 50 wheel support therefor, a driving rear wheel support therefor, a motor mounted on said frame, a tool supporting frame comprising drawbars having a universal connection with said frame, a rear cross member, brackets connecting said member 55 to said drawbars, and a yoke bolted to said drawbars intermediate their ends, apertured brackets secured to said cross member near each end thereof, cross bars passing through each bracket and pivoted at their inner ends to said cross member, 60 each cross bar having an apertured boss at its outer end, bolts passing through said apertured bosses and aligned apertures in said cross member, compression springs held between nuts on said bolts and said cross member, lift arms adjustably mounted on said frame, each having a pivotal connection with one of said cross bars, a circle 65 revolvably mounted in said first named brackets and said yoke, and an earth engaging tool supported from said circle.

2. In a road machine, a frame, a front support therefor, a rear support therefor, an earth-engaging tool, a tool supporting frame, a draft connection from said first frame to said tool supporting 70

frame, supports for said tool supporting frame adjustably mounted on opposite sides of said first frame, and connections from said supports to said tool supporting frame each comprising a bar pivotally connected to the associated support and having a pivotal connection and a spring connection with said tool supporting frame.

3. In a road machine, a frame, a front support therefor, a rear support therefor, an earth-engaging tool, a tool supporting frame, a draft connection from said first frame to said tool supporting frame, supports for said tool supporting frame adjustably mounted on opposite sides of said first frame, connections from said supports to said tool supporting frame each comprising a bar pivotally connected to the associated support, a pivotal connection between said bar and said tool supporting frame, a spring connection between said bar and said tool supporting frame, and means on said tool supporting frame for limiting movement of said bars.

4. In a road machine, a frame, a front support therefor, a rear support therefor, a tool, means for supporting said tool from said frame comprising a pair of lift arms adjustably mounted on said frame, connections from said arms to said tool, each connection including a member pivotally connected to the associated lift arm, a pivotal connection between said member and said tool and a resilient connection between said member and said tool limiting relative pivotal movement between said member and said tool about the axis of said pivotal connection.

5. In a road machine, a frame, supports therefor, a tool, a draft connection from said frame to said tool and a flexible connection between said frame and said tool including a bar having a pivotal connection at one end to said tool and an elastic connection thereto at the other end.

6. In a road machine, a frame, supports therefor, a tool including a cross member having a plurality of connecting stations at each end, adjusting means on said frame including a pair of lift arms, a connecting member associated with each lift arm and having connecting stations corresponding to the connecting stations on the adjacent end of said cross member, and means for establishing a connection between selected corresponding stations on said cross member and said connecting members, certain pairs of said stations being adapted with said connection establishing means to provide a flexible support for said tool and other pairs of said stations being adapted with optional connection establishing means to provide a rigid support for said tool.

7. In a road machine, a frame, supports therefor, a tool, a yielding connection between said tool and said frame, and means for rendering said yielding connection rigid.

8. In a road machine, a tool support, a tool including planing means having a plurality of cutting edges, means for adjusting the depth of cut of said planing means, and means for maintaining said cutting edges parallel to the finished surface of the road, comprising an internally threaded housing pivotally secured to said tool support and a bolt having threaded engagement with said housing and universally connected to said tool, said maintaining means being positioned between said tool and said tool support and being subjected to tension or compression stresses only.

9. In a road machine, a tool support, a tool including planing means having a plurality of cutting edges, means for adjusting the depth of

cut of said planing means, and means for maintaining said cutting edges parallel to the finished surface of the road, consisting of a member pivoted to said support and a second member pivoted to said tool, said members having threaded engagement, said maintaining means being positioned between said tool and said tool support and being subjected to tension or compression stresses only.

10. In a road machine, a tool support, a tool including planing means having a plurality of cutting edges, means for adjusting the depth of cut of said planing means, and means for maintaining said cutting edges parallel to the finished surface of the road, comprising an internally threaded housing pivotally secured to said tool support and a bolt having threaded engagement with said housing and universally connected to said tool, and means including said housing for clamping said bolt in adjusted position.

11. In a road machine for planing and resurfacing a road during traverse thereof, a tool support, a tool frame, planing means and distributing means connected to said tool frame, means to adjust said planing means to a position parallel with the finished surface of the road including an internally threaded housing depending from said support and a screw pivoted to said frame and having threaded engagement with said housing, and means to adjust said distributing means to create a road surface in a selected plane including a journal on said frame, a second housing rotatably mounted in said journal and having internal threads, a bolt pivoted to said distributing means and having threaded engagement with said second housing.

12. In a road machine for planing and resurfacing a road during traverse thereof, a tool support, a tool frame, planing means mounted on said frame, distributing means pivotally connected to said frame, means to adjust said distributing means to create a road surface in a selected plane including a journal on said frame, a housing rotatably mounted in said journal and having internal threads, a bolt pivoted to said distributing means and having threaded engagement with said housing.

13. In a road machine, a tool frame, a tool, means for adjusting said tool relatively to said frame comprising a support pivoted in said frame, a member journaled in said support and having a handle, a second member pivoted to said tool and having threaded engagement with said first member for adjustment with respect thereto, and means comprising said support and said handle for locking said members in adjusted position.

14. In a road machine, a frame, front and rear supports therefor, an earth-engaging tool, a tool supporting frame, a draft connection from said first frame to said tool supporting frame, supports for said tool supporting frame adjustably mounted on opposite sides of said first frame, and means connecting said supports to said tool supporting frame, each connecting means comprising a member pivotally connected to the associated support and having a pivotal connection and a resilient connection with said tool supporting frame.

15. In a road machine, a frame, front and rear supports therefor, an earth-engaging tool, a tool supporting member, a draft connection from said frame to said tool supporting member, supports for said tool supporting member adjustably mounted on opposite sides of said frame, and means connecting said supports to said tool supporting

member, each connecting means comprising a connecting member pivotally connected intermediate its ends to the associated support and having a pivotal connection at one end, and a resilient connection at the other end with said tool supporting member.

16. In a road machine, a frame, front and rear supports therefor, an earth-engaging tool, a tool supporting member, a draft connection from said frame to said tool supporting member, supports for said tool supporting member adjustably mounted on opposite sides of said frame, and means connecting said supports to said tool supporting member, each connecting means comprising a connecting member pivotally connected to the associated support and having a pivotal connection and a resilient connection with said tool supporting member.

17. In a road machine, a frame, front and rear supports therefor, an earth-engaging tool, a tool supporting member, a draft connection from said frame to said tool supporting member, supports for said tool supporting member adjustably mounted on opposite sides of said frame, means connecting said supports to said tool supporting member, each connecting means comprising a connecting member pivotally connected to the associated support and having a pivotal connection and a resilient connection with said tool supporting member, and means for limiting movement of said connecting members with respect to said tool supporting member.

18. In a road machine, a frame, a front support therefor, a rear support therefor, a tool, means for supporting said tool from said frame comprising a pair of lift arms adjustably mounted on said frame, connections from said arms to said tool, each connection including a member pivotally connected to the associated lift arm, a pivotal connection between said member and said tool and an elastic connection between said member and said tool, said elastic connection resisting relative oscillatory movement of said member and said tool about the axis of said pivotal connection.

19. In a road machine, a frame, a front support therefor, a rear support therefor, a tool, adjustable means for supporting said tool on said frame, and connecting means from said supporting means to said tool, comprising a member having a pivotal connection with said supporting means, and spaced connections to said tool, one of said spaced connections being resilient, the other of said spaced connections being pivotal.

20. In a road machine, a frame, supports therefor, a tool, a draft connection from said frame to said tool, and a flexible connection between said frame and said tool, including a member having spaced connections to said tool, one of said connections being pivotal, and the other of said connections being resilient.

21. In a road machine, a frame, supports therefor, a tool, a draft connection from said frame to said tool, and means for supporting said tool from said frame including a pair of members, and means connecting said members for relative pivotal movement comprising spaced connections therebetween, one of said connections being flexible and the other of said connections being pivotal.

22. In a road machine, a frame, supports therefor, a tool, a draft connection from said frame to said tool, means for supporting said tool from said frame including a pair of members, and means connecting said members for relative

pivotal movement comprising spaced connections therebetween, one of said connections being flexible and the other of said connections being pivotal, and means for limiting relative pivotal movement between said members.

23. In a road machine, a frame, supports therefor, a tool, a draft connection from said frame to said tool, means for supporting said tool from said frame including a pair of members, and means connecting said members for relative pivotal movement comprising spaced connections therebetween, one of said connections being flexible and the other of said connections being pivotal, and optional means for preventing relative pivotal movement of said members.

24. In a road machine, a frame, front supports for said frame, rear supports for said frame, an earth-engaging tool, a draft connection from said frame to said tool, supports for said tool adjustably mounted on said frame, and means for connecting said supports to said tool, each connecting means having a pivotal connection with the associated support, a pivotal connection with said tool, and a resilient connection with said tool, all of said connections being separated.

25. In a road machine, a frame, a front support therefor, a rear support therefor, a tool, adjustable means for supporting said tool on said frame, and connecting means from said supporting means to said tool, comprising a member having a pivotal connection with said supporting means, and spaced connections to said tool, one of said spaced connections being resilient, another of said spaced connections being pivotal, and a third of said spaced connections providing an optional rigid support for said tool.

26. In an automotive road machine, a frame, resilient front supports for said frame, resilient rear supports for said frame, an earth-engaging tool, means for supporting said tool resiliently from said frame, comprising a pair of members, a pivotal connection between said members, and a resilient connection between said members spaced from said pivotal connection, said supporting means absorbing vibration of said frame to prevent transmission thereof to said tool.

27. In an automotive road machine, a frame, resilient front supports for said frame, resilient rear supports for said frame, an earth-engaging tool, means for supporting said tool resiliently from said frame, comprising spaced pivotal and resilient connections, said supporting means absorbing vibration of said frame to prevent transmission thereof to said tool.

28. In a road machine, a frame, front supports for said frame, rear supports for said frame, an earth-engaging tool, a draft connection from the front end of said frame to said tool, means for supporting said tool adjustably from said frame, comprising means for adjusting said tool vertically with respect to said frame, and means for adjusting said tool laterally with respect to said frame; said supporting means including resilient connections between said tool and said frame for absorbing vibrations of said frame to prevent transmission thereof to said tool, said adjusting means acting through said resilient connections.

29. In a road machine, a frame, front supports for said frame, rear supports for said frame, an earth-engaging tool, a draft connection from the front end of said frame to said tool, means for supporting said tool adjustably from said frame, comprising means for adjusting said tool vertically with respect to said frame, means for

- adjusting said tool laterally with respect to said frame; said supporting means including resilient connections between said tool and said frame for absorbing vibrations of said frame to prevent transmission thereof to said tool, said adjusting means acting through said resilient connections, and means for optionally disabling said resilient connections whereby a rigid connection is provided from said frame to said tool in any adjusted position thereof.
30. In a road machine, a frame, front supports for said frame, rear supports for said frame, an earth-engaging tool, a draft connection from the front end of said frame to said tool, means for supporting said tool adjustably from said frame, comprising means for adjusting said tool vertically with respect to said frame, means for adjusting said tool laterally with respect to said frame; said supporting means including a pair of members, and pivotal and resilient connections between said members for absorbing vibrations of said frame to prevent transmission thereof to said tool, whereby said tool has a floating engagement with the surface of the road.
31. In a road machine, a frame, front supports for said frame, rear supports for said frame, an earth-engaging tool, a draft connection from the front end of said frame to said tool, means for supporting said tool adjustably from said frame, comprising means for adjusting said tool vertically with respect to said frame, and means for adjusting said tool laterally with respect to said frame; said supporting means including flexible connections between said frame and said tool to prevent transmission of vibration of said frame to said tool thereby providing a floating engagement of said tool with the surface of the road, said adjusting means acting through said flexible connections.
32. A unitary automotive road machine, comprising a frame, resilient front supports for said frame, resilient rear supports for said frame, an earth-engaging tool, a tool supporting member, a draft connection from said member to said frame, lift devices on said frame, and resilient connections from said lift devices to said member, said resilient connections supporting a part of the weight of said tool and said tool supporting member during operation of said machine in maintaining road surfaces.
33. In a road machine, a frame, front supports for said frame, rear supports for said frame, an earth-engaging tool, a tool supporting member, a draft connection from said tool supporting member to said frame, lift devices on said frame, and resilient connections from said lift devices to said member, including resilient elements, said elements resisting upward movement only of said lift devices.
34. In a road machine, a frame, front supports for said frame, rear supports for said frame, an earth-engaging tool, a tool supporting member, a draft connection from said tool supporting member to said frame, lift devices on said frame, resilient connections from said lift devices to said member, and means for adjusting said tool laterally with respect to said frame including a shift link connected to one of said resilient connections.
35. In a road machine, a frame, front supports for said frame, rear supports for said frame, an earth-engaging tool, a tool supporting member, a draft connection from said tool supporting member to said frame, lift devices on said frame, resilient connections from said lift devices to said member, each connection including an element pivotally and resiliently connected to said member, and means for adjusting said tool laterally with respect to said frame including a link connected to one of said elements.
36. In a road machine, a frame, ground supports for said frame, an earth-engaging tool, a tool supporting member, a draft connection from said frame to said member, second and third members, each of said second and third members having a pivotal and a resilient connection with said first member adjacent the respective ends thereof, a pair of lift devices mounted on said frame connected said second and third members respectively, and means for adjusting said tool laterally with respect to said frame including a shift link connected to one of said second and third members.
37. In a road machine, a frame, ground supports for said frame, an earth-engaging tool, a tool supporting member, a draft connection from said frame to said member, second and third members, each of said second and third members having a pivotal and a resilient connection with said first member adjacent the respective ends thereof, a pair of lift devices mounted on said frame connected to said second and third members respectively, and means for adjusting said tool laterally with respect to said frame including a shift link adapted for optional connection to said second member and said third member.
38. In a road machine for planing and resurfacing a road during traverse thereof, an earth-engaging tool comprising a plurality of cutting edges lying in a plane, wheeled supports for said tool, and connecting means from said tool to said supports including a member having horizontally spaced pivotal and resilient connections with said tool.
39. In a road machine for planing and resurfacing a road during traverse thereof, an earth-engaging tool comprising a plurality of cutting edges lying in a plane, front and rear supports for said tool, and connecting means from said tool to said supports comprising a pair of members, a pivotal connection between said members, and a resilient connection between said members spaced from said pivotal connection and limiting relative pivotal movement of said members about the axis thereof.
40. In a road machine for planing and resurfacing a road during traverse thereof, a plurality of cutting edges, frame members for rigidly supporting said edges, wheeled frame means for supporting said members for mobility, and resilient connections between said frame member and said frame means, each connection including a pair of members pivotally and resiliently connected at spaced points.
41. In a road machine, a tool support, a tool including planing means having a plurality of cutting edges, means for adjusting the depth of cut of said planing means, and means for maintaining said cutting edges parallel to the finished surface of the road, consisting of a member pivoted to said support, a second member pivoted to said tool, said members having threaded engagement, and means comprising one of said members for clamping said members in adjusted position.
42. In a road machine, a tool support, a tool including planing means having a plurality of cutting edges, means for adjusting the depth of cut of said planing means, and means pivotally connected to said tool and said support for maintaining said cutting edges parallel to the finished

surface of the road, comprising an internally threaded housing and a bolt having threaded engagement therewith, and means including said housing for clamping said housing and said bolt in adjusted position.

43. In a road machine, a frame, supports for said frame, a ground-engaging tool, means for movably connecting said tool to the frame whereby contact of the tool with the ground is effected solely by the weight of said tool, resilient means acting in a direction to oppose the weight of said tool, and means for rendering said resilient means ineffective or placing a predetermined adjustment thereon while maintaining said movable connection, to compensate for varying conditions of ground surface.

44. In a road machine adapted for planing and resurfacing a road during traverse thereof, a frame, supports for said frame, an earth-engaging tool comprising a plurality of cutting edges lying in a plane, means for supporting said tool from said frame for vertical and lateral adjustment with respect thereto, and resilient connections between said supporting means and said tool acting in a direction to oppose the weight of said tool.

45. In a road machine adapted for planing and resurfacing a road during traverse thereof, a frame, resilient supports for said frame, an earth-engaging tool comprising a plurality of cutting edges lying in a plane, means for supporting said tool from said frame for vertical and lateral adjustment with respect thereto, and resilient connections between said supporting means and said tool for absorbing vibrations of said frame to prevent transmission thereof to said tool, whereby said tool has a floating engagement with the surface of the road.

46. In a road machine adapted for planing and resurfacing a road during traverse thereof, a frame, resilient supports for said frame, an earth-engaging tool comprising a plurality of cutting edges lying in a plane, means for supporting said tool from said frame for vertical and lateral adjustment with respect thereto, means for movably connecting said tool to said supporting means whereby contact of the tool with the ground is effected solely by the weight of said tool, resilient means acting in a direction to oppose the weight of said tool, said resilient means being adjustable to support varying portions of the weight of said tool while maintaining said movable connection, to compensate for varying conditions of ground surface.

47. In a road machine, a frame, supports for said frame, an earth-engaging tool, a draft connection from said frame to said tool, and means for supporting said tool from said frame for vertical and lateral adjustment with respect thereto, said supporting means including resilient elements, all said resilient elements acting only in a direction to oppose the weight of said tool, and absorbing vibrations of said frame to prevent transmission thereof to said tool.

48. In a road machine, a frame, supports for said frame, a tool, a tool supporting member, a plurality of connecting stations on said member, means for supporting said tool supporting member from said frame, including a connecting member having connecting stations corresponding to

said connecting stations on said tool supporting member, and means for establishing a connection between selected corresponding stations on said tool supporting member and said connecting member, certain of said stations being adapted with said connection establishing means to provide a flexible support for said tool supporting member and said tool.

49. In a road machine, a frame, supports for said frame, a tool, a tool supporting member, a plurality of connecting stations on said member, means for supporting said tool supporting member from said frame, including a connecting member having connecting stations corresponding to said connecting stations on said tool supporting member, and means for establishing a connection between selected corresponding stations on said tool supporting member and said connecting member, certain pairs of said stations being adapted with said connection establishing means to provide a flexible support for said tool supporting member and said tool, and other pairs of said stations being adapted with optional connection establishing means to provide a rigid support for said tool supporting member and said tool.

50. In a road machine, a frame, supports therefor, a tool, a tool supporting member, means for supporting said tool supporting member on said frame, and connecting means from said supporting means to said tool supporting member, comprising a connecting member movably connected to said supporting means and to said tool supporting member, resilient means controlling relative movement of said connecting member with respect to said tool supporting means, and means for limiting such relative movement.

51. In a road machine, a frame, supports therefor, a tool, a tool supporting member, means for supporting said tool supporting member on said frame, and connecting means from said supporting means to said tool supporting member, comprising a connecting member movably connected to said supporting means and to said tool supporting member, and resilient means controlling relative movement of said connecting member with respect to said tool supporting means, said resilient means acting only to oppose the weight of said tool supporting member and said tool.

52. In a road machine, an earth-engaging tool structure, resilient means opposing the weight of said structure for resiliently supporting said structure with the tool in floating engagement with the ground, and means for imposing on said resilient means only a portion of the structure weight which would otherwise be imposed thereon.

53. In a road machine; an earth-engaging tool structure; lift means for said structure; resilient means opposing the weight of said structure for resiliently supporting said structure with the tool in floating engagement with the ground; and leverage mechanism cooperating with said lift means, said resilient means and said structure for imposing on said resilient means only a portion of the structure weight which would otherwise be normally imposed thereon.

CARL A. GUSTAFSON.

CERTIFICATE OF CORRECTION.

Patent No. 1,999,189.

April 30, 1935.

CARL A. GUSTAFSON.

It is hereby certified that error appears in the printed specification of the above numbered patent requiring correction as follows: Page 1, second column, line 47, for "total" read tool; and page 7, second column, line 14, claim 36, before "said" second occurrence insert the word to; and that the said Letters Patent should be read with these corrections therein that the same may conform to the record of the case in the Patent Office.

Signed and sealed this 25th day of June, A. D. 1935.
